(57) **CLAIM**

The ornamental design for a battery cable assembly for jump starting device, as shown and described.

DESCRIPTION

FIG. 1 is a perspective view of a new design for battery cable assembly for a jump starting device;

FIG. 2 is a rotated perspective view thereof;

FIG. 3 is a front elevational view thereof of FIG. 1;

FIG. 4 is a top plan view thereof of FIG. 1;

FIG. 5 is a bottom plan view thereof of FIG. 1;

FIG. 6 is a left side elevational view thereof of FIG. 1;

FIG. 7 is a right side elevational view thereof of FIG. 1;

FIG. 8 is a perspective view of a clamp portion thereof, shown in a closed position, and shown in isolation for ease of illustration;

FIG. 9 is an exploded view of FIG. 8;

FIG. 10 is another perspective view of FIG. 8, with the clamp in an open position;

FIG. 11 is another perspective view of FIG. 10;

FIG. 12 is a top and perspective view of a new design for battery cable assembly for a jump starting device, with the cord shown in a coiled position;

FIG. 13 is a perspective view thereof of FIG. 12; and,

FIG. 14 is another perspective view thereof of FIG. 12, shown without the clamps for ease of illustration.
